SPRING HEEL FOR FOOTWEAR

Herbert H. Smith, Bay Shore, N. Y.

Application July 21, 1947, Serial No. 762,387

5 Claims. (Cl. 36—35)

1

This invention relates to spring heels for footwear, whereby high efficacy is obtained in regard to the prevention and/or absorption of foot shock to the individual while walking, standing or working.

The present invention provides variations in and improvements to the spring heel forming the subject matter of my prior U. S. Patent No. 2,441,039.

It is an object of the present invention to provide a simple arrangement for the connection of a spring within a rubber heel, wherein mere flexures of the heel permit assembly of all parts to confine the spring within the heel preparatory to and during attachment of the heel to a shoe.

It is another object of the present invention to provide a spring heel the parts of which are capable of assembly as just stated, and also of disassembly by a similar procedure, so that the spring arrangement can be easily removed from the heel and a spring arrangement of a different tension and size can replace the original spring, whereby the heel can be adapted to the use of persons of different weights and manners of walking.

According to the present invention, a combination is provided which, retaining certain of the features of my prior patent aforesaid, modifies others of such features in important particulars.

Thus here, as in said prior patent, a recess is formed in the heel for receiving the spring arrangement, the bottom of this recess being at the bottom of the heel; and such heel bottom protrudes to some extent below the side edges of the heel. Also here, as in said copending application, the spring arrangement comprises two plates and a spring disposed therebetween and is housed in said recess. But, according to the present invention, the shaping of the protruded heel portion is changed, to obtain a better spring behavior as a result of a freer resilient action of the rubber heel body.

Also here, as in said prior patent, the spring arrangement is held in the recess by means provided upon or adjacent to the heel recess wall so as to retain the spring arrangement in temporary engagement with the heel; but, whereas in my said prior patent, a turnable part is partially turned incidental to employment of said means for placing the spring arrangement in temporary engagement with the heel, here such a rotative movement of a turnable part is not necessary. Instead, mere heel flexures are utilized for rendering the spring retaining means effective.

Also here, as in said copending application, a

2

conical coil spring is the working part of the spring arrangement; but here the placement of the coils of the spring of maximum and minimum diameter are reversed as compared with their placement in said copending application, thereby obtaining improved spring action in regard to the minimization of shocks and jars through the rubber heel to the heel of the person wearing a shoe equipped with the new spring heel.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a top plan view of one form of heel pursuant to the present invention.

Fig. 2 is a transverse vertical section, taken on the line 2—2 of Fig. 1.

Fig. 3 is a longitudinal vertical section, taken on the line 3—3 of Fig. 1.

Fig. 4 is a view similar to Fig. 3, but showing the heel attached to the bottom of a shoe by means of the usual brads or nails and washers.

Fig. 5 is a bottom plan view of the heel.

Fig. 6 is a view similar to Fig. 1, but showing a modification of the present invention.

Fig. 7 is a transverse sectional view taken on the line 7—7 of Fig. 6.

The spring heel, according to the form of the invention shown in Figs. 1 to 5, includes a rubber heel body 10 having a recess 11 therein adapted to receive a spring arrangement 12. This rubber heel is made of rubber which has some resiliency but has less resiliency than the spring arrangement 12. The bottom of the recess is formed from heel material 13 and this material protrudes downwardly from the side edges of the heel whereby to provide for a play of the material on the bottom of the heel so that the person may rest his weight upon the spring arrangement 12.

It is pointed out that such bottom protrusion 13 from the heel 10, while flat at its own bottom surface, is established by a straight wall bevel 14 extending all around the heel, and is of circular area, with the center thereof substantially vertically below the center of the circular bottom of the recess 11. Thus the bevel 14 is at a substantially constant angle all around the curved back of the heel and partially along both sides of the heel.

The recess 11 has a main cylindrical side wall

and below the latter a frusto conical side wall, at the lower reduced end of which last-mentioned side wall is the circular bottom of the recess.

The spring arrangement 12 includes a conical coil spring 15 and two circular plates or discs 16 and 17.

The plate or disc 16 is circular and shaped to include a hollow upstanding annular rib 18 concentric with the disc and spaced somewhat inwardly from the rim of the disc. Within this rib, therefore, is provided a shallow cylindrical seat open at its top for receiving the lower end of the spring 15.

The plate or disc 17 is circular and shaped to include a downwardly facing shallow cylindrical seat established by an annular vertical wall 19 concentric with the disc, beyond which wall is an annular rim portion 20. This seat is for receiving the upper end of the spring 15.

It will be noted that the spring receiving seat in the disc 17 is of greater diameter than that of the spring receiving seat in the disc 16; with the diameter of the former seat conforming to that of the larger end of the spring 15 and the diameter of the latter seat conforming to that of the smaller end of the spring. Hence the spring body flares upwardly in the heel 10, with the result that the functioning of the spring, in transmitting shocks and jars received at the bottom of the heel, is a force dissipating one. The spring transmits a shock or jar divergently upward for distribution thereof over the bottom area of the heel of the wearer, with a consequent reduction in intensity.

Through the body of the heel 10 surrounding the recess 11 are a plurality of apertures 21, here shown as eight in number, through which apertures are sent the nails 22 for attaching the heel to a shoe, so as to bury the nail heads, together with the washers 23, in the rubber body of the heel.

Such heel attachment is done while the spring arrangement 12 is held in the recess 11.

The means for thus retaining the spring arrangement 12 comprises a series of projections 24 carrying terminal lips inwardly directed to slightly overlap at their flat bottoms the top of recess 11. The upper portions of these lips are downwardly beveled at 25. Interveningly of the projections 24 are cut outs, countersunk portions or recesses 26. Thus the heel is lightened in weight and made more freely flexible, yet masses of rubber material, constituted by the projections 24, are present at the points where the nails or brads 22 are to be driven through the heel and at which points the washers 23 are embedded through which the nails or brads 22 are to be extended. At the same time, the lips underlying the bevels 25 and carried by the projections 24 are rather thin and of a cross section tapering toward the interior of the recess 11.

In order to dispose the spring arrangement 12 for dependable retention in the recess 11, it is merely necessary, with the top of said recess uppermost, to place the lower disc 16, the spring 15 and the upper disc 17 in said recess, and then flex the heel 10 to some convexity at its upper side, one or more times, along a line diametral to the recess 11 or along several such lines, thus to readily catch the rim portion 20 of the upper disc 17 under all the six beveled lips at the inner ends of the projections 24. It is also possible to force the disc 17 into place without flexing

the heel 10, especially by machine assembly. When the heel is cast in a mold the bevel of the lips will be smooth enough to allow this.

To remove a spring arrangement 12 and substitute another, all that need be done is to perform one or more flexings of the heel as just described.

According to the modification of Figs. 6 and 7, the heel body, here marked 10', has a bottom protrusion 13' like that at 13. As will be noted, the spring arrangement 12 is shown exactly as above described. Here, however, the side wall of the spring receiving recess has an overhanging continuous circular lip 27 having a beveled top 28.

Between the apertures 21 for the attaching nails or brads, and between the periphery of the heel and the outer limits of the lip 27, recesses 29 may be provided as shown, for lightening the weight of the heel 10 while in use, thereby also saving rubber and yet preserving rubber masses at the points of application of the attaching nails or brads.

The recesses 29, it will be observed, are shown as of about half the depth of the recesses 26.

The heel of the present invention, like that of my prior patent aforesaid, may be sold as a unit, for ready attachment to leather members 30 on the bottom of a shoe 31, as by means of the brads 22 and washers 23.

The discs and the spring of the spring arrangement may be covered with soft pliable material such as cotton, felt or woolen fabric, or plastic. The spring may be made of any size and the wire can be either of round or flat sections.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A spring heel arrangement comprising a heel formed of resilient material, a recess within the heel having its bottom closed to provide at the bottom of the recess a body of resilient material adapted to be compressed inwardly within the recess as the shoe is worn and weight placed upon the shoe heel, a spring arrangement disposed within the recess and adapted to be compressed as the shoe is worn, means for securing the heel to a shoe bottom, said spring arrangement comprising two plates and a coil spring extended between the two plates, the plate in the open end of the recess being connected to the side wall of the recess whereby to temporarily retain the spring arrangement within the resilient heel material at least until the heel has been secured to the shoe, said plate adapted to engage with heel material portions, said portions overhanging the top of the recess and being spaced around the recess, said plate being a circular disc of uninterrupted circularity around its periphery, there being minor recesses in the top of the heel beyond the spring receiving recess, said minor recesses spaced around the last-named recess in alternation with said overhanging heel material portions.

2. A spring heel comprising a resilient heel body for attachment to the heel area of a shoe

and formed with a recess which opens through the top wall of the heel body, a pair of superimposed plates within said recess, resilient means disposed between said plates and normally urging them apart, means on the adjacent faces of said plates holding said resilient means centrally in position therebetween, and spaced projections formed with the walls of the heel body defining said recess and having flexible lips overlying the exposed face of the topmost plate of said pair of plates releasably retaining said topmost plate in position within said recess against the action of said resilient means.

3. A spring heel, comprising a heel body formed of resilient material for attachment to the heel area of a shoe and formed with a circular recess in the center portion thereof and which opens through the top wall of the heel body, vertically spaced metallic plates within said recess, a coil spring mounted between said metallic plates, and means integrally formed with the walls of said heel body defining said recess and overlying the top face of the topmost of said plates to retain the topmost plate within the recess against the action of said coil spring, whereby flexing said heel body will disengage said means from the top face of said topmost plate and free said plates and said coil spring to be removed from said recess, said means comprises a plurality of projections integrally formed with said heel body and extended radially of said recess, and lips at the inner ends of said projections overlying the top face of said topmost plate.

4. A spring heel, comprising a heel body formed of resilient material for attachment to the heel area of a shoe and formed with a circular recess in the center portion thereof and which opens through the top wall of the heel body, vertically spaced metallic plates within said recess, a coil spring mounted between said metallic plates, and means integrally formed with the walls of said heel body defining said recess and overlying the top face of the topmost of said plates to retain the topmost plate within the recess against the action of said coil spring, whereby flexing said heel body will disengage said means from the top

35

face of said topmost plate and free said plates and said coil spring to be removed from said recess, said means comprises a plurality of projections integrally formed with said heel body and extended radially of said recess, and lips at the inner ends of said projections overlying the top face of said topmost plate, said projections being separated by minor recesses in the top face of said heel body about said first-named recess.

5. A spring heel, comprising a heel body formed of resilient material for attachment to the heel area of a shoe and formed with a circular recess in the center portion thereof and which opens through the top wall of the heel body, vertically spaced metallic plates within said recess, a coil spring mounted between said metallic plates, and means integrally formed with the walls of said heel body defining said recess and overlying the top face of the topmost of said plates to retain the topmost plate within the recess against the action of said coil spring, whereby flexing said heel body will disengage said means from the top face of said topmost plate and free said plates and said coil spring to be removed from said recess, said means comprises a plurality of projections integrally formed with said heel body and extended radially of said recess, and lips at the inner ends of said projections overlying the top face of said topmost plate, said projections radially outwards of said lips being formed with openings for the passage of nails for securing the heel body to the shoe.
